WITNESS:

R. E. Wise

UNITED STATES PATENT OFFICE.

JACOB F. GRASLEY, OF ZANESVILLE, OHIO.

SOCKET WRENCH.

Application filed April 18, 1925. Serial No. 24,199.

This invention relates to improvements in tools for use upon socket wrenches and which includes the conventional form of rectangular extension which is adapted to be fitted 5 within the upper end of the socket wrench and which further includes a skirt or sleeve which extends along the entire length of the rectangular portion in spaced relation therefrom and includes correspondingly 10 shaped inner edges thereon in order that the end of the socket may be received on the rectangular lug and within the correspondingly shaped space between the lug and the skirt or sleeve in order that the upper end 15 of the socket wrench will not be caused to break or crack and prevent rotation of the rectangular lug portion within the upper portion of the socket wrench.

With the above and other objects in view, 20 the invention further includes the following novel features and details of construction, to be hereinafter more fully described, illustrated in the accompanying drawing and pointed out in the appended claim.

25 In the drawing:—

Figure 1 is an elevation of my invention showing the same applied to a socket.

Figure 2 is a fragmentary section of my invention showing the manner in which the 30 upper end of the socket wrench is received within the lower end of my tool.

Figure 3 is a bottom plan view of my invention per se.

Referring to the drawing in detail, where- 35 in like characters of reference denote corre- responding parts, the reference character 10 indicates a bar having a rectangular or square portion 11 provided upon the upper end thereof and which is adapted to be re- ceived within the jaws of a monkey wrench 40 and the like and which further includes an enlarged portion 12 upon the opposite end thereof. The invention residing in the pro- vision of this enlarged portion 12 upon the 45 lower end of the bar of the tool 10 and which includes a rectangular lug portion 13 arranged therein and extending in spaced relation therein from a correspondingly shaped recess 14 provided within the en- 50 larged portion 12.

As clearly illustrated in Figure 2 of the drawing the upper end 15 of a socket wrench 16 receives the rectangular portion 13 and also received within the correspondingly shaped groove or space 14 provided around 55 the rectangular portion 13 within the enlarged portion or sleeve 12 in order that this socket 16 when engaging or being placed upon its work and being rotated with the tool 10 will turn freely therewith without 60 the usual danger of splitting its upper portion 15 owing to the fact that this portion may be snugly received within the space or groove 14 and engage the inner and outer 65 sides thereof.

It will thus be noted from the foregoing description and accompanying drawing that this invention provides a very useful device 70 for use in machine shops and garages and which will save the buying of various sizes of socket wrenches owing to the fact that the same wrenches may be used indefinitely owing to the fact that this tool will prevent the splitting of the upper ends thereof. It is further to be noted that this invention is 75 very simple in construction, easy to manufacture and owing to the simple construction thereof, may be manufactured in great numbers and sold at a very nominal cost.

The invention is susceptible of various 80 changes in its form, proportions and minor details of construction, and the right is herein reserved to make such changes as properly fall within the scope of the appended claim.

Having described my invention what is 85 claimed is:—

A tool comprising a bar provided with a rectangular tool engaging portion upon one end, a sleeve of enlarged dimensions being 90 carried upon the opposed end of the bar, and a lug projected from the bar and within the sleeve being adapted to provide a recess therebetween within which may be received the attaching portion of a socket wrench to 95 preserve the corners thereof and to prevent bulging which frequently results in loose fitting connections.

In testimony whereof I affix my signature.

JACOB F. GRASLEY.
